UNITED STATES PATENT OFFICE.

GEORGE D. JOHNSTONE, OF DENVER, COLORADO.

TRAMWAY FOR HOISTING AND DUMPING APPARATUS.

SPECIFICATION forming part of Letters Patent No. 694,551, dated March 4, 1902.

Application filed June 10, 1901. Serial No. 64,030. (No model.)

To all whom it may concern:

Be it known that I, GEORGE D. JOHNSTONE, a citizen of the United States, residing at 1349 South Fifteenth street, in the city of Denver, 5 in the county of Arapahoe and State of Colorado, have invented a new and useful tramway for hoisting and dumping apparatus for the use on mines or other places where ore, dirt, or other material is to be hoisted, carried away, and dumped, of which the following is a specification.

My invention relates to improvements in the handling of and dumping of ores and other material which may be hoisted from 15 mines and other excavations and which is to be carried away and dumped or unloaded, and is especially adapted to those mines or other excavations where a bucket elevated by a cable or rope is used.

20 The object of my invention or improvement is to provide a means for taking the bucket, filled with ore, dirt, or other material, away from the mouth of the shaft or other excavation and deposit the contents of said bucket at a place desired, all of which is to be accomplished automatically with the exception of the power that is exerted by steam or other agency in hoisting the bucket and its contents from the shaft or other excavation. 25 I attain these objects by the mechanism illustrated in the accompanying drawings, in which the figures represent the several parts of the machine and refer to the same part in each illustration.

30 Figure 1 represents a side elevated view of the machinery the same as when erected and in operation at a mine or other excavation. 14 represents the cable; 13, the sheave; 16, the bucket; 16^a, the bail or handle of the bucket; 17, the short rope or cable attached to the bottom of the bucket and at the end of which is attached an iron or wooden ball 17^a. 7 is an upright timber or beam supported by another beam 8, which, together with the sheave, form 35 what is known as a "gallows-frame." 5 represents the beam, upon which an iron rail 6 is laid, said beam and rail being supported by standards 7 and 9. Fig. 1 shows but one side, as both the gallows-frame and track or 40 rails are double—that is, two upright timbers 7, two supports 8, two rails 6, two beams 5, &c., which, standing side by side or running

parallel, constitute the mechanism which supports the cable and carrier 15, which is handling the bucket and so trammimg and 55 dumping the ore or other material. 15 is the carrier, and 12 and 12^a the device used in dumping the bucket. Where 14 15 16^a 16 and 17 and 17^a are in heavy lines, it represents the position of the machinery when the bucket 60 has been hoisted and before it has passed down the track or rails. The dotted lines show the position after the carrier has carried the bucket down the track or rails and dumped or unloaded the same. 65

Fig. 2 is a sectional end view of the track, showing the upright supports 9, which may be made of wood or iron, the beam or rail-supports 5, and the rails 6, and 10 the cross-beam, hereinafter mentioned. 70

Fig. 3 represents the dumping and unloading device 12 and 12^a, attached to the beams 5. This device consists of substantial iron rods, flat or round, extending below the track sufficiently to permit of a free passage of the 75 bucket within the same as they extend downward, 12, and above that portion which extends at right angles to 12, and is in shape as represented by 12^a.

Fig. 4 represents a side view of the carrier 80 15. 18 is the carrier-wheels; 18^a, the point of axis, pivot, or shaft for each of said wheels; 15^a, one side of the carrier, or what may be termed "side plate." 20^c is the lever which operates the clutch 20, hereinafter mentioned. 85 The carrier-wheels are ordinary flanged iron wheels, such as are used on ore-cars, railroad-cars, &c. The pivots, side plates, and lever are made of iron or other material, as may be desired. Fig. 4 is the view along the line X 90 X shown in Fig. 8 and shows the position of the wheels before the weight of the bucket or bucket and its contents fall upon it, and 6^a shows bend or notch in track and rails for holding wheels farthest from lever 20^c and 95 designed to hold the carrier on the track and rails until forced forward, as hereinafter described. In this figure (Fig. 4) the catch or starter has been omitted and is shown by Figs. 9 and 10. 100

Fig. 5 is the same view of carrier and track as Fig. 4, but with the weight of the bucket or bucket and contents resting on the carrier. The weight has changed the center of

gravity of the carrier, elevated the wheels farthest from lever 20°, and depressed or lowered wheels nearest said lever. In this figure the catch or starter has been omitted.

5 Fig. 6 is an interior view of the carrier along line Y Y shown in Fig. 8. In this figure, 18 represents carrier-wheels. 19 represents sheave in carrier for cable; 20, clutch; 20^a, open groove in clutch, in which is pin 21
10 to regulate the distance the clutch may move in either direction. 20^b is clutch-lever; 6, rail; 5, track-beam or bed; 18^a, pivots, &c. 14^a shows position of iron ball on cable or rope as it rests on sheave and clutch. In this position the carrier supports the bucket or bucket and its contents and is as it is in passing down the incline rails or track. In this figure the catch or starter has also been omitted.

Fig. 7 is the same machine, showing the 20 cross-beam 10, which is at the end of the rails or track or placed at the point where the bucket is to be dumped and the beam against which the lever 20^b strikes and in so striking throws the clutch 20 from the position shown in Fig. 6 to the position shown in Fig. 7. In this figure the catch or starter has also been omitted.

Fig. 8 is looking down on the top of the carrier, but does not show the catch or starter.

25 Fig. 9 shows substantially the same as Fig. 6, with the addition of the catch or starter 23.

Fig. 10 shows the catch or starter, which is an iron rod bent to the shape represented by 23 and 23^a in Fig. 10, which is attached to the 30 pivot 22, which is adjusted in the side plates 15^a of the carrier, so that the same will rise and fall when acted upon by the iron ball 14^a. It will be observed that the cable or rope passes through the starter at or near the point 35 23^a and that the starter 23 is only acted upon when the ball 14^a is elevated. In Fig. 9 the heavy lines show the starter at rest. (See heavy lines 23.) The dotted lines 23 show the starter elevated by the iron ball 14^a, which 40 in so acting lifts the back portion of the carrier, and the tension or strain on the cable of the cable so acting on the starter gives the carrier a forward motion, starting it down the incline track or rails. It will also be observed that the same impetus is given to the 45 carrier when the bucket is loaded and the weight thereof falls upon the clutch, changing the center of gravity to a point in front of the middle wheels, as shown in Fig. 5.

50 The mechanism used in this invention consists of what is known as an ordinary "gallows-frame" equipped with a cable or rope, to which is attached a bucket, and which, in connection with some power, such as steam 55 or other, is used in hoisting or raising ore, dirt, or other material, and to which has been added an incline track or inclined rails, at the top of which incline is the bend or notch, (6^a, Figs. 4 and 5,) equipped with a carrier and 60 dumping device, as shown in the illustrations, together with an iron ball, which is bolted to the cable or rope above the bucket, and also

65 with a short cable or rope attached to the bottom of the bucket and on the end of which is attached an iron or wooden ball. The carrier itself consists of two heavy iron plates or sides properly adjusted together by means of the pivots or axles of the six flange-wheels which support the carrier in its movements up and down the track or rails. Between the 70 two plates or sides of the carrier is the T-shaped clutch 20, acting upon the pivot or axle 18^a, and the pin 21, which is firmly fixed in the side plate 15^a and operates in the groove 20^a. Also between said plates or sides 75 of the carrier is the sheave 19, which revolves upon its pivot or axle and upon which the cable or rope acts when the bucket is being dumped, &c.

To understand the operation of the above 80 mechanism and to see the results attained, let us note the following illustration: We are at a shaft over which has been erected the gallows-frame and incline track and the same equipped with a cable, carrier, dumping device, sheave, bucket, and iron balls above mentioned and depicted in Fig. 1. The power to lower and raise the bucket is at the other end of the cable or rope and operated by an engineer. The cable itself passes from the 85 power up and oversheave 13, then passes down through the carrier, between the two sides or plates thereof, and between the sheave 19 and the clutch 20, which brings it also between the two rails of the track on down to where 90 it is attached to the bail of the bucket 16^a. Before using the machinery the engineer will see that the iron ball 14^a is below the track. The position of the carrier will then be as in Fig. 4, its weight resting upon the four rear flange-wheels, with the two rear wheels resting in 95 the bend or notch 6^a in the rails 6. The clutch 20 will then by force of its own weight rest against the rope or cable, as in Fig. 6. (Note, however, that the iron ball 14^a will 100 be below and not as seen in Fig. 6.) It will now be observed that the bucket can be lowered or raised without affecting the carrier until such time as the engineer shall raise the bucket so far as to bring the ball 14^a 105 up through the carrier and beyond the clutch 20. Suppose the bucket at the bottom of the shaft and loaded. The engineer starts the power and the bucket is raised. In passing up the ball 14^a passes through the carrier, 110 slightly raises the clutch 20, and passes out above the carrier. As soon as it has passed through the carrier clutch 20 falls back against the cable or rope to the position shown in Fig. 6. The engineer reverses the power 115 and the ball descends and presses on the top of clutch 20 and against the sheave 19 at a point on said sheave slightly above a line drawn horizontally through its center, so that it is then in the position represented in Fig. 6, 120 with the entire weight of the bucket and its contents resting on the top of clutch 20 and the sheave 19. When the weight so falls upon the clutch and sheave, it brings the center of 125 130

gravity of the carrier to the front of the two middle flange-wheels and nearer to the lever 20°. By so doing it presses down the two front wheels or those near lever 20° and raises the rear wheels out of the notch 6^a, and the engineer by allowing the cable or rope to run out (owing to the space between the tracks or rails being free of all cross-beams or obstructions) permits the carrier, with its burden, to pass down the incline rail 6. The carrier in so passing down the incline carries the bucket along under the track and between the two arms of the dumper 12 12 and over that portion of the dumper 12^a in Fig. 3. As the bucket passes through the dumper the rope at the bottom of the bucket passes into 12^a, Fig. 3, where it must remain by reason of the ball 17^a. The carrier, with its burden, passing on down incline strikes the lever 20° against the cross-beam 10, which immediately acts upon clutch 20, raising the same, which liberates the ball 14^a and allows the bucket to descend, and in its descent it is turned upside down by reason of the ball 17^a being held in the dumper 12^a, as shown by the dotted lines in Fig. 1. In case the bucket had been raised from the shaft empty and there had not been sufficient weight lowered onto the front part of the carrier to start it down the incline the engineer would simply raise the bucket so high that the ball 14^a would catch in the starter 23, Fig. 9, and by raising still higher the starter would raise the rear end of the carrier and so start it forward on the track. The bucket having been unloaded, it would hang, as per the dotted lines in Fig. 1, with the ball 14^a as there shown, and the position of the clutch 20 would be as shown in Fig. 7, or closed to receive the ball at the lower part thereof. The engineer then exerts the power the same as if raising the bucket from the shaft, the bucket ascending toward the carrier, the ball 14^a comes in contact with the clutch 20 and sheave 19, as shown in Fig. 7, and not being able to pass through the carrier and the power still being applied drags the carrier back up the incline or track and throws it into its original position, as in Fig. 1, and, being relieved of its burden, the carrier drops into the notch or bend in the track or rails 6 on its rear wheels, as in Fig. 4. The engineer then reverses the power, lowers the bucket, and the ball descends from its position, as in Fig. 7. Clutch 20, then released, falls of its own weight and is in position to permit the ball again to pass up through, when the bucket ascends with a new load. The carrier is made of sufficient weight to overcome all tendency to start back up the incline from cable tension before compelled to do so by reason of the ball and clutch position shown in Fig. 7. In case the incline track is extended so far that there would be a tendency on the part of the rails to spread the uprights 9 are extended above the track far enough to permit of cross ties or beams being bolted across the tops, leaving room for

the carrier to pass between the uprights and below the cross-beams.

I am aware that vertical hoists or gallows-frames are used and that buckets are dumped by man-power and by other devices, such as a rope and hook attached to a ring in the bottom of the bucket, and that tracks are laid upon the ground and at elevations and ore 75 and other material trammed and dumped by man-power and in other ways; also, that a machine has been patented for self-dumping, in which the sheave 13 in Fig. 1 is in a car or frame on wheels and drawn toward the 80 engine or power; but it does not carry to the dump nor away from the power and is in the nature of a movable sheave-wheel, such as 13 in Fig. 1, only that in Fig. 1 it is permanent, nor has any machine a carrier in any 85 way similar to the one in this invention, so with all of those I have nothing to do; but

What I do claim as my invention, and desire to secure by Letters Patent, is—

1. In a hoisting, conveying and dumping apparatus, an inclined raised track having a depressed portion, in combination with a carrier having wheels at one end adapted to rest in said depressed portion and raise wheels on the opposite end of said carrier from said track, a receptacle depending from a rope, and means connected with said rope and carrier for suspending said receptacle from said carrier so as to tilt and start the latter, substantially as described. 100

2. In a hoisting, conveying and dumping apparatus, an inclined track with a depression at its upper end, a tilting carrier having wheels adapted to rest in said depression, a lifting-rope passing over a pulley on said carrier and carrying a load-receptacle at its lower end, a pivoted clutch on said carrier, and a ball on said rope adapted to engage said pulley and clutch, said parts being combined substantially as described. 105

3. In a hoisting, conveying and dumping apparatus, an inclined track, a carrier thereon, a lifting-rope passing over a pulley on said carrier and having a load-receptacle at its lower end, a dumping device in the path 115 of said carrier adapted to engage a depending projection on said receptacle, locking means including a pivoted clutch for engaging a ball on said rope for sustaining said receptacle in elevated position during the 120 transit of said carrier, and a stop for engaging said clutch for releasing the same and thereby permit the lowering of said rope so as to in connection with said dumping device dump said receptacle, said parts being combined substantially as described. 125

In testimony whereof I have signed my name to this specification in the presence of two subscribing witnesses.

GEORGE D. JOHNSTONE.
